ATTACHMENT FOR GARMENT HANGERS

Duward G. Ellison, Tulsa, Okla.

Application May 6, 1940, Serial No. 333,636

2 Claims. (Cl. 223—88)

My invention relates broadly to garment hangers and more particularly to an auxiliary garment supporting device adapted to support a pair of trousers, or the like, from an ordinary coat hanger.

An important object of my invention is the provision of an attachment for a coat hanger that may be easily and conveniently attached to an ordinary coat hanger, and that will properly support a skirt, pair of trousers, or the like, in an upright position.

Another object of my invention is the provision of an attachment for a coat hanger that may be easily attached or disengaged from any coat hanger of ordinary design and construction.

Still another object of my invention is the provision of an attachment for a coat hanger that will hold the garment in such a way as to preclude the possibility of its accidental removal.

Yet another object of my invention is the provision of an attachment for a coat hanger that is resilient in its action to hold the garment in a taut condition thereby alleviating the possibility of disarranging or rumpling the fabric.

A further object of my invention is the provision of an attachment for a coat hanger that is simple in construction, efficient in operation and inexpensive to manufacture.

Other objects and advantages of my invention will be apparent during the course of the following description.

In the drawing, forming a part of this specification, and in which like numerals are employed to designate like parts throughout the same,

Figure 1 is a front elevation of a device embodying my invention, and showing the same attached to a coat hanger, and

Figure 2 is a perspective view of my device.

In the accompanying drawing, wherein for the purpose of illustration, is shown a preferred embodiment of my invention, the numeral 10 designates a coat hanger of ordinary design and construction preferably made from a wire rod and including a bottom rod 11 and inwardly convergent top rods 12 and 13 the upper ends of which are twisted together as at 14. The extremity of the arm 12 extends beyond the twisted portion 14 and is fashioned into a goose neck formation 15 which provides a means for supporting the hanger from a suitable support.

The numeral 16 designates an auxiliary attachment for the hanger 10 and may be fashioned from a single piece of wire rod, or the like. The horizontally disposed middle portion 17 of the at-

5 tachment 16 is of sufficient length to traverse the twisted portion 14 of the hanger 10 and is integrally connected to and spaced laterally of the resilient arms 18 and 19 by the U-shaped hook portions 20 and 21. The arms 18 and 19 extend divergently downwardly to a point substantially under either extremity of the bottom rod 11 of the hanger 10, and the ends 22 and 23 thereof, disposed at right angles thereto in a direction away from the middle portion 17, are fashioned into substantially S-shaped hooks 24 and 25. The portions 26 and 27 of the S-shaped hooks 24 and 25 are adapted to receive the bottom rod 11 of the hanger 10 and the portions 28 and 29 thereof are 10 adapted to receive and support a skirt, pair of trousers, or the like.

In the use of the attachment, the hooked portions 20 and 21 at either end of the transversely positioned middle portion 17 are adapted to engage the hanger 10 at the shoulders 30 and 31 at 15 either side of the twisted portion 14, and the hooked portions 26 and 27 at the lower ends of the arms 18 and 19 engage the bottom rod 11. The trousers 32 are folded to preserve the creases 20 in the front and rear of the legs and to bring belt loops 33 and 34 at the front and rear of the trousers into engagement with the hooked outer ends 28 and 29 of the attachment.

The arms 18 and 19 are essentially resilient 25 in their nature so that the rod engaging portions 26 and 27 may be moved toward each other by bending the bottom rod 11 of the hanger into a V-shaped formation and in the direction of the hook 15. When the hook portions 28 and 29 of 30 the attachment receives the loops of the trousers, the bottom rod 11 of the hanger may be bent in a direction away from the hook 15 to spread the said hooked ends of the attachment in a manner 35 to hold the said trousers in a taut or stretched condition therebetween to substantially preclude the accidental removal of the trousers therefrom and to prevent the disarranging or rumpling 40 of the fabric.

It is to be understood that the form of my invention, herewith shown and described, is to be 45 taken as a preferred example of the same, and that various changes in the size, shape and arrangement of parts may be resorted to without departing from the spirit of my invention, or the 50 scope of the appended claims.

Having thus described my invention, I claim:

1. In combination with a garment hanger including a bottom rod and upwardly converging top rods, a supplementary supporting member 55 formed at its middle with a laterally extending

hook portion adapted to receive the said top rod adjacent their point of convergence, and resilient arm members extending divergently downwardly from the hook portion and terminating in laterally extending S-shaped hook formations the inverted U-shaped portions of which receive the said bottom rod of the hanger.

2. In combination with a garment hanger including a bottom rod and upwardly converging top rods, a supplementary supporting member adapted to detachably engage the top rods at their point of convergence and having resilient

arm members extending divergently downwardly therefrom and terminating in a right-angularly positioned S-formation, the inverted U-shaped portion of which receives the bottom rod of the hanger in a manner whereby the lower ends of the arms may be moved toward or away from each other against the resilient action of the arms by bending the bottom rod of the hanger so that when a garment is attached to the U-shaped portion of the said hooked ends the arms will hold the garment in a taut condition.

DUWARD G. ELLISON.
